UNITED STATES PATENT OFFICE.

JOHN MURTON BROWN, OF IRVINGTON, NEW JERSEY, ASSIGNEE TO CRYSTAL OIL BURNER CORP., OF IRVINGTON, NEW JERSEY, IN CORPORATION OF NEW JERSEY.

OIL BURNER.

Application filed July 23, 1925. Serial No. 45,453.

This invention relates to an oil burner employing fluid fuel such as a viscous oil and is an improvement on the burner set forth in my copending application, Serial No. 696,5187, filed March 1, 1924.

An object of the present invention is to provide a highly efficient and practical burner of simplified construction.

Another object of the invention is to provide a fuel inlet and outlet in such relation to each other and to a heated area as to maintain a saturated vapor in contact with said heated area for effecting the substantial complete conversion of the vapor into a gas.

Another object of the invention is to provide a burner having a firepot adapted to have other firepots added thereto.

Another object of the invention is to provide a plurality of firepots with a common chamber for converting liquid or carburetted fuel substantially completely to a gas.

Another object of the invention is to provide an oil burner which may be quickly and conveniently applied to the firebox of a steam or other boiler for the generation of heat in place of coal or other hard fuel.

Another object of the invention is to provide an oil burner having a "cracking chamber" so disposed with respect to the firepot as to be out of the direct path of the flame issuing therefrom but arranged to form a compact unit.

Another object of the invention is to provide an oil burner capable of converting liquid fuel substantially completely to gaseous fuel without being dependent upon the heat developed by the burner for effecting such conversion.

Another object of the invention is to provide an oil burner with means for "cracking" liquid fuel which is adjacent to but not in the direct path of the flame of said burner.

Another object of the invention is to provide an oil burner with an "oil cracking" chamber which is maintained at the "cracking" temperature by means independent of a burner.

Another object of the invention is to provide an oil burner which is substantially noiseless in operation.

Other objects of the invention will be apparent as the description is read.

In the manufacture of an oil burner it is desirable to obtain simplicity and efficiency as well as durability. The feature of sim-

plicity is particularly important when the burner is to be used by a layman, as in connection with a home heating system.

Although my burner as shown in the above-mentioned copending application has given satisfactory service in demonstrating my broad idea, I have found that in so far as structural features are concerned the invention herein shown and described provides a more simple and practical burner of such a character as to be easily handled and readily applied to a variety of conditions.

My improved burner may be comprised of several separable parts which may be renewed when necessary in a convenient and expeditious manner.

The burner parts include a "cracking" chamber to receive a mixed fuel for conversion into the gaseous state, said chamber being supported by a conduit which in turn is associated with one end of a base casting comprising a firepot.

One of the novel features of the present burner resides in disposing the "cracking" chamber adjacent to but not directly over the firepot and the provision of independent means for maintaining the "cracking" chamber at the proper temperature to effect the conversion of the liquid fuel into gas. In addition the "cracking" chamber is so designed as to retain the vaporized fuel in a zone of intense heat until it is completely converted into gas. Another novel feature resides in providing in addition to the independent means for heating the "cracking" chamber an auxiliary flame derived from the "cracked" fuel.

The present type of burner is perfected to the point where it is substantially noiseless in operation, thus eliminating one of the main objections to oil burners, particularly when employed for household purposes.

The invention will be more fully understood by reference to the accompanying drawings in which

Fig. 1 is a side elevational view of a burner embodying my invention;

Fig. 2 is a plan view of the burner shown in Fig. 1.

Fig. 3 is an enlarged sectional view of the burner taken on a vertical median plane;

Fig. 4 is a sectional view taken on line IV-IV in Fig. 1;

Fig. 5 is a perspective view of the present burner employing a plurality of firepots;

Fig. 6 is a sectional view taken on line VI—VI in Fig. 3;

Fig. 7 is a side view of the duplex nozzle showing the Bunsen burner inlet;

Fig. 8 is a diagrammatic representation of the burner unit showing the relative positions of the elements and the direction of flow of the gases;

Fig. 9 is a fragmentary view of the fuel inlet pipe partly broken away to show vanes or baffles, and

Fig. 10 is a view taken on line X—X in Fig. 9.

As illustrated, a burner unit constituting an embodiment of my invention may comprise an upper or fuel receiving member or element 9 and a lower or fuel discharging member or element 10 including a firepot 11. The fuel receiving member may comprise a chamber 12 offset from and in communication with a vertical conduit 13 which may be made integral with the chamber 12 (see Fig. 3). The chamber may be of any suitable configuration and as shown is substantially of cylindrical form and provided with a slightly tapered aperture 12' in its upper wall to receive what may be termed a nozzle 14 at one end of an inlet pipe 15.

The nozzle 14 extends into the chamber 12 a distance sufficient to bring the outlet orifice of the nozzle into close proximity to the lower wall 18 of the chamber. This lower wall, which is of relatively small area, plays an important part in the operation of the burner. As will presently be set forth, the wall 18 constitutes what may be termed a "hot spot" or restricted heated area against which the mixed fuel or saturated vapor is discharged at high velocity from the nozzle 14, so as to produce a "cracking" effect causing the mixed fuel to be converted into gas. This gas then passes through an opening or chamber outlet 19 and into passage 13 for entrance to the lower member for discharge from the firepot of the fuel discharging element. An important feature of the present construction is the provision of a large discharge conduit which permits the converted fuel to pass from the "cracking" chamber without any compressive or back pressure upon the in-flowing vapors.

Especial note is to be made of the construction of the chamber 12 in that it is designed to retain the fuel vapor or carburetted fuel within the chamber and in contact with the "hot spot" until the fuel is substantially completely converted into gas. For example, the wall separating the chamber from the discharge conduit is made sufficiently high to prevent the escape of the heavier particles of oil and thus retain the same in the lower portion of the chamber against the highly heated portion. Furthermore, the inlet nozzle is disposed very close to the bottom of the chamber thus bringing

the carburetted fuel into direct contact with the heated spot. Means to be more fully described hereinafter are provided to maintain every portion of the bottom of the chamber at a high temperature so that any vapor striking the bottom of the chamber at any point will receive the action of the intense heat thereof.

The firepot 11 may be a single casting or may be composed of two parts 21 and 22 connected in any suitable manner as, for example, by tap bolts 22' shown in Fig. 4. The part 21 may comprise a wedge-shaped hollow body open at its wider end, an aperture 23 which may be tapered being provided in the normal upper wall of the body to receive the vertical conduit 13 which may be secured against lateral movement by properly positioned set screws 24 disposed in threaded apertures in a vertical flange 25 integral with and extending from the converging edges of the hollow body of the part 21. This flange in conjunction with a flange 26 on the part 22 provides a continuous enclosure, a portion 27 of which serves as a crater or mouth for the expulsion of ignited gases.

The part 22 which includes the firepot 11 of the burner comprises a bowl portion 28 having a slightly tapered seat 29 about its upper inner periphery to receive a perforated nozzle-plate 31. The nozzle-plate in conjunction with the bowl 28 provides what may be termed the firepot or chamber to receive gases from within the hollow body 21 through passages 32 and 33 (see Fig. 4). These passages are arranged to direct the gases to opposite sides of the bowl 28 causing them to circulate for passage through all the perforations in the nozzle-plate. These perforations are disposed in predetermined relative positions and extend through the nozzle-plate at certain angles as will be later described.

As above mentioned the chamber 12 is offset with respect to the conductor 13. The bottom wall 18 of the chamber 12 may be positioned over a duplex nozzle 34 of one side of the nozzle-plate 31. Thus as will be seen the chamber 12 is so disposed as to be adjacent to but out of the direct path of heat radiated vertically from the nozzle-plate or firepot.

The duplex nozzle may be comprised of double cylindrical walls 39 and 39' to provide an internal supplemental or fuel passage 35 and an outer surrounding auxiliary gas chamber 36. The duplex nozzle may be provided with a reduced portion 37 fitted to a recess 38 in the top wall 39 of the hollow portion 21. The passage 36 of the duplex nozzle 34 is provided with an upper perforated wall 41 having a plurality of outlet orifices 42 and is connected to a pipe or other conduit 43 to receive for discharge, a continu-

uous auxiliary fuel supply to produce flames 44 for heating the wall or hot spot 18 of the chamber 12. The auxiliary fuel may be had from any suitable constant source (not shown) and may be the ordinary illuminating gas as commonly supplied by public service gas companies or the gas may be generated by suitable apparatus as an accessory of the present burner, as for example an oxy-acetylene or other gas-producing system. When the gas is from a house supply line the gas may be mixed with oxygen by means of the usual type of Bunsen burner inlet to the nozzle, it being desirable to obtain an exceedingly hot flame to maintain the chamber at the desired temperature to effect the "cracking" operation.

The central passage 35 of the duplex burner is provided with a wall 45 having angularly disposed apertures 46 to direct discharged ignited gas so that flames 40 therefrom impinge upon the inner periphery 47 of an enlarged portion 48 of the central passage. The central portion of the duplex burner 34 receives a portion of the gas from the chamber 12 by way of the conduit 13 as it passes for discharge from the nozzle-plate 31 when the burner is in operation. The auxiliary or constant fuel supply serves to heat the hot spot 18 of the chamber 12 and also serves to provide pilots for igniting the gases discharged from the burner or nozzle-plate 31. The pilots are, as shown, in the form of passages 51 so arranged as to direct flames 50 toward apertures 52 of the burner plate and across an absorbent ring to be later described. The apertures 52 are as shown in Figs. 2 and 3 arranged in such angular relation that the gas from one aperture is discharged toward the gas discharged from an adjacent aperture. By this arrangement when the discharge from one aperture is ignited by the pilot flames 50 the discharge from each of the apertures 52 will be ignited in rapid succession.

The additional apertures 53 and 54 in the nozzle-plate are disposed in circular concentric rows and, as shown, may be in staggered relation. The apertures 54 direct discharges or flames toward a point just outside of the perimeter of the flange 26 and the apertures 53 direct the flames against the inner surface of the said flange just below its edge. Thus during operation of the burner the flange is maintained at a high temperature and aids in quickly starting the burner after the intervals in which the burner fuel is cut down during operation by automatic means and then turned on, governed by the temperature of an apartment which is to be maintained uniform.

The apertures in the nozzle-plate may of course be disposed at any desired angle, depending upon the particular use or furnace into which the burner unit is to be

placed. The present type of nozzle-plate may be made with the apertures arranged to give a concentrated heat output as when the burner is used under a crucible to melt metal, or the apertures may be so disposed as to cause a wide spread of heat over a larger area, such as is necessary to heat the water tubes of a boiler. The removability of the nozzle makes it convenient to quickly adapt a unit for use under various conditions since nozzle-plates with differently disposed holes may be kept in stock to be substituted to meet the particular duty to which the burner is to be subjected.

Under certain conditions it may be desirable to cut off a row of apertures and in the present burner this may be readily accomplished by providing a removable cap 56 as shown in Fig. 3 to fit a projection or knob 55. The cap 56 may have a continuous flange 57 to cover and close the entire row of holes 54 or the flange may be cut away so that only a portion of the apertures may be covered, for example every alternate aperture. The knob 55 may be provided with an aperture 58 to receive an instrument to facilitate removal of the plate 31.

It has been found desirable to provide a ring of asbestos or other non-combustible material 59 between the lower portion of the flanges 26 and the outer edge of the nozzle-plate 31. This asbestos ring is absorbent and if the burner is started up "cold" any gas that may condense by reason of the cold nozzle-plate will flow downwardly and become absorbed by the ring 59 which thus functions as a wick. As soon as any appreciable amount of oil has accumulated in the wick it is ignited by the pilot flames 50 and as the flame travels around the wick it serves to ignite the discharged gas from the apertures in the burner or nozzle-plate 31.

It is to be understood that the amount of condensed gas or liquid fuel that accumulates in the wick is very small and soon disappears as the burner becomes heated and goes into full operation. No fuel can remain in the wick owing to the intense heat generated by the burner. The condensed fuel is partially prevented from passing through the apertures 53 and 54 of the nozzle-plate by an interiorly disposed annular shoulder 31' extending around and adjacent to the outer edge of the plate to deflect the fuel and cause it to pass through the apertures 52. If any considerable amount of liquid should accumulate beneath the wick 59, it may be drawn off through an outlet pipe 61'.

As above set forth the present burner provides a constant source of heat from the circularly disposed flames 44 beneath the bottom "hot spot" 18 of the chamber 12. For the purpose of obtaining a uniform distribution of heat throughout the "hot spot" the lower surface of the "hot spot" is pro-

vided with a plurality of tapered fins 61 radiating from an enlargement or boss 62. This construction provides a greater mass of material at the central or hottest portion of the flames of the duplex nozzle. This results in the tendency toward a thermal balance or equal distribution of heat over the hot spot and also provides the hottest zone at the point where the mass of vaporized fuel first strikes the "hot spot". The under surface of the hot spot, or bottom of the chamber 12 is also provided with concave depressions between the fins 61, the curvature of these depressions extending outwardly toward the outer periphery of the bottom of the chamber. By reason of this construction the flame from the duplex nozzle will be given a "fountain" formation which prevents the cold air from striking the hot spot.

The chamber 12 and "hot spot" 18 as employed in the present invention may be used for supplying the gaseous fuel to a plurality of firepots or heating elements 22. As shown in Fig. 5 additional firepots 63 and 64 have been added to the firepot 22.

The chamber 12 and "hot spot" 18 which serves as a superheater for the fuel mixture may, if desirable, be proportionately enlarged if a battery of firepots is employed. The hot spot or heated area may be corrugated or even of cone shape, the object being to provide such heated surface for the discharge of fuel thereagainst, it being understood that the formation of the surface may vary.

An important feature of the invention resides in the provision of means within the fuel inlet pipe 15 for preventing denser portions of the fuel from accumulating on the bottom of the pipe or conduit. In the present construction I have shown a plurality of spaced vanes 65 consisting of flat pieces of sheet metal extending across the pipe and raised from the bottom thereof to provide restricted openings 66. The vanes are disposed at an angle to the longitudinal axis of the pipe. As the fuel passes through the pipe 15 any portion which may condense and drop to the bottom of the pipe is interrupted by the vanes and by reason of the angular position of the vanes, is either atomized, torn up or deflected to the main stream of fuel and carried to the burner. The vanes or deflector members may be of any suitable shape, the object being to prevent an accumulation of heavy fuel along the bottom of the conduit.

In the operation of the present burner as the flames 44 serve to initially heat the hot spot 18 and the fuel mixture is driven at relatively high velocity from the nozzle 14 against the hot spot, this mixture, which is in a vapor state, strikes the "hot spot" and is converted into gas. The wall 65 prevents

a direct flow of the gases to the conduit 13 thus causing the gas to swirl about the chamber and be thoroughly subjected to the effect of the hot spot so that any portion of the vapor which has not been "cracked" or gasified is converted into a gas. During the starting of the burner the mixed fuel travels over the relatively cold portions of the burner parts on its way to the outlet apertures in the nozzle-plate and some of the gas may be condensed as it leaves said outlet apertures which condensate flows toward and is absorbed by the wick 50 and is immediately ignited by the pilot flame 50 which flames are continually in operation as are the flames 44 by reason of the gas entering the chamber 36 of the duplex nozzle.

As the hot spot becomes heated to an increasingly higher temperature the mixed gases impinging thereagainst are cracked and produce a highly combustible gas. This gas being discharged through the nozzle-plate 31 and the aperture 46 in the duplex nozzle 34 is ignited by the auxiliary burner flames 44 and 50. The hot spot which during the operation of the burner is subjected to the heat of the auxiliary flames 44 and the flames 40 of the duplex nozzle reaches an extremely high temperature resulting in an attenuated gaseous mixture giving an intensely hot flame with substantially complete combustion without residue or unburned particles of carbon.

The present construction of burner is particularly adapted for domestic use and lends itself well to automatic control since the hot spot may be maintained at a sufficiently high temperature so that although the fuel supply may be cut off or reduced for relatively long periods the burner may be quickly put into operation at maximum efficiency. The pilots also serve to ignite the gas from the burner in the event that the fuel supply be accidentally cut off and subsequently caused to flow.

As will be readily seen the present construction provides separable parts capable of renewal with a minimum of labor or expense. The nozzle-plate 31 which may be subject to the most wear owing to the ravages of the flames may be easily replaced by another plate without disturbing any of the other elements of the burner.

Modifications of the invention may occur to those skilled in the art, but such as fall within the scope of the appended claims are contemplated as coming within the spirit of my invention.

What is claimed is:

1. An oil burner comprising a supply conduit for a mixture of fuel oil and air, a "cracking" chamber connected to said conduit for converting a mixture of fuel oil and air into gas, and a firepot for burning said gas, said "cracking" chamber being offset

with respect to said firepot, and means independent of said firepot for maintaining said "cracking" chamber at a sufficiently high temperature to effect the conversion of the 5 mixture of fuel oil into gas.

2. An oil burner comprising a supply conduit for a mixture of fuel oil and air, a "cracking" chamber connected to said conduit for converting a mixture of fuel oil 10 and air into gas, a firepot for burning said gas, and duplex means for burning a portion of said gas and for burning gas supplied from an outside source for maintaining said "cracking" chamber at a sufficiently high 15 temperature to effect the conversion of the mixture of fuel oil into gas.

3. An oil burner comprising a supply conduit for a mixture of fuel oil and air, a "cracking" chamber connected to said conduit for converting a mixture of fuel oil 20 and air into gas, a firepot for burning said gas, said cracking chamber being removed from the flames issuing from said fire pot and an independent heat source for heating 25 said cracking chamber.

4. An oil burner comprising a supply conduit for a mixture of fuel oil and air, a "cracking" chamber connected to said conduit for converting a mixture of fuel oil 30 and air into gas, a firepot for burning said gas, said "cracking" chamber being offset with respect to said firepot and means in 35 said chamber for maintaining said mixture of fuel oil and air in said chamber until the same is substantially completely converted into gas.

5. An oil burner comprising a supply conduit for a mixture of fuel oil and air, a "cracking" chamber connected to said conduit, said chamber having an outlet, said cracking chamber, supply conduit and outlet being so related with respect to each other 40 as to maintain said mixture of oil and air in said chamber until the same is substantially 45 completely converted into gas, a discharge conduit connected to said chamber, and a firepot connected to said discharge conduit.

6. An oil burner comprising a supply conduit for a mixture of fuel oil and air, a

"cracking" chamber connected to said conduit, said conduit having its end extending into said chamber into close proximity to the bottom thereof, a discharge conduit connected to said chamber near the top thereof, a burner connected to said chamber for receiving gas therefrom for heating said chamber, and a firepot connected to said discharge conduit. 50

7. An oil burner comprising a supply conduit for a mixture of fuel oil and air, a "cracking" chamber connected to said conduit, said conduit having its end extending into said chamber into close proximity to the bottom thereof, a discharge conduit connected to said chamber near the top thereof, a 55 burner connected to said chamber for receiving gas therefrom for maintaining said chamber at the desired temperature, said burner being provided with independent means for providing heat for said chamber, 60 and a firepot connected to said discharge conduit. 65

8. An oil burner comprising a supply conduit for a mixture of fuel oil and air, a "cracking" chamber connected to said conduit, said conduit having its end disposed within said chamber so as to direct the mixture of fuel oil and air directly against the bottom thereof, a discharge conduit connected to said chamber near the top thereof, 70 a firepot connected to said discharge conduit, and means for maintaining said chamber at the "cracking" temperature. 75

9. An oil burner comprising a supply conduit for a mixture of fuel oil and air, a "cracking" chamber connected to said conduit, said conduit having its end disposed within said chamber so as to direct the mixture of fuel oil and air directly against the bottom thereof, a discharge conduit connected to said chamber near the top thereof, 80 a firepot connected to said discharge conduit, and an auxiliary firepot for said chamber disposed intermediate said discharge conduit and said firepot and being located 85 beneath said chamber. 90

In testimony whereof I affix my signature.
JOHN MURTON BROWN.
